Primary Examiner — Patricia Palasik(74) *Attorney, Agent, or Firm* — Bachman & LaPointe, PC(57) **CLAIM**

The ornamental design of a gearing, as shown and described.

DESCRIPTION

FIG. 1 is a front view showing the ornamental design of a gear in accordance with the present invention;

FIG. 2 is a side view of the design of FIG. 1;

FIG. 3 is a perspective view of the design of FIG. 1;

FIG. 4 is a rear view of the design of FIG. 1;

FIG. 5 is a top view of the design of FIG. 1;

FIG. 6 is a bottom view of the design of FIG. 1; and,

FIG. 7 is a reverse side view of the design of FIG. 1.

The broken lines in the drawings depict unclaimed environmental subject matter.
